REACTANCE TUBE MODULATION

Original Filed Dec. 27, 1939

UNITED STATES PATENT OFFICE

2,349,811

REACTANCE TUBE MODULATION

Murray G. Crosby, Riverhead, N. Y., assignor to
Radio Corporation of America, a corporation
of Delaware

Original application December 27, 1939, Serial No.
311,074, now Patent No. 2,278,429, dated April
7, 1942. Divided and this application March 7,
1942, Serial No. 433,745

7 Claims. (Cl. 179—171.5)

This application concerns new and improved reactance tube circuits of the nature of those described in my United States application #136,578, filed April 13, 1937, now U. S. Patent No. 2,279,659, dated April 14, 1942, and in my United States application #209,919, filed May 25, 1938, now United States Patent No. 2,250,095, dated July 22, 1941. The present application is a division of my United States application #311,074 filed December 27, 1939, now U. S. Patent No. 2,278,429, dated April 7, 1942.

A two-tube balanced reactance tube arrangement is disclosed which is differentially modulated by the control potentials, but the modulation produced by undesired tube element voltage variations (not to be confused with control potentials) is cophasal so that the stability of a frequency modulated oscillator is not impaired by the reactance tubes.

A feature of my application is a circuit arrangement wherein the modulating potentials are applied between a control electrode of one of the tubes and ground. This permits one side of the modulation circuit to be maintained at ground potential yet provides differential modulation of the reactance tubes.

In the balanced reactance tube circuits small linear reactive changes can be obtained with change of control potentials so that the said circuits may be used to control the tuning of a tuned circuit to accomplish phase modulation of wave energy thereon. My application also discloses new and improved phase and frequency modulation systems using the balanced reactance tube arrangement.

All of the modifications shown may be used in automatic frequency control circuits operating on a heterodyning oscillator in a receiver as well as in frequency or phase modulation circuits as disclosed in application No. 136,578, filed April 13, 1937, now U. S. Patent No. 2,279,659, dated April 14, 1942.

In describing my invention in detail, reference will be made to the attached drawing wherein:

Figure 1 illustrates an improved reactance tube circuit cooperating with a source of modulating potentials and an electron-coupled oscillation generator to modulate the frequency of operation of the latter.

Figure 2 illustrates a novel circuit arrangement comprising two reactance tubes in a balanced circuit which has a stabilizing effect on the oscillation generator circuits with a novel phase shifting circuit and novel modulation circuit. In this

figure a novel frequency modulation system is also included.

Figure 3 is a modification of the arrangement of Figure 1; while Figures 3a and 3b are curves and graphs used to explain the operation of the reactance tube circuits.

In Figure 1, tube 1, which is the reactance tube, is of the pentode-tube type and has its anode 2 coupled by a condenser 3 to a tuned circuit 5 comprising inductance L2 and capacity C2. The circuit 5 connects the grid 8, cathode 10, and screen grid 12 of an electron-coupled oscillator tube 20 in regenerative circuits for the production of oscillations. The cathode 22 of the reactance tube 1 is coupled to circuit 5 also so that the reactive effect produced in tube 1 is of the oscillation generation circuit 5. The control grid 24 of tube 1 is coupled to the circuit 5 by phase shifting condenser C and the tuned reactance comprising inductance L1 and condenser C1. Modulating or control potentials to control the reactive effect are supplied at 26 to the control grid 24.

Tube 1 is the reactance tube which produces the reactive effect in its plate circuit. The feedback phase shifter consists of capacitance C and tuned circuit L1—C1 shunted by resistance R. That is, high frequency voltage from the circuits of tube 20 is supplied to the anode 2 of tube 1 and through the phase shifter circuit including C, L1, C1, and R to the grid of tube 1. This phase shifter is of the constant-current type in which the reactance of the capacitance C is made large compared to the impedance of the tuned circuit L1—C1. The capacitive reactance, therefore, determines the phase of the current in the said circuit so that the potential drop across the resistive tuned circuit L1—C1, which is resonated at the frequency for which the reactive effect is being obtained, takes the phase of the current and leads the plate voltage by practically 90°. Since the current pulses which reach the anode 2 lead the voltage on the said anode by about 90°, a reactive effect is produced in the tube and this reactive effect, which is in this case capacitive, is effective in the circuit L2—C2 which controls the frequency of operation of the oscillation generator. The degree of reactive effect is controlled by the bias potentials on the grid 24. If the grid is made more positive the reactive effect increases. If the grid becomes more negative the reactive effect is decreased.

If the frequency range over which the reactance is to operate is large compared to the selectivity of circuit L1—C1, the damping effect

of R may be increased by making R lower. If a smaller range of frequency control, but a high sensitivity to control potential is desired, resistor R may be removed completely. Reducing the value of C increases the reactive effect, but unless the reactance of C is made large compared to the impedance of the tuned circuit, a resistive effect is introduced in the variable reactance effect provided by the tube 1.

Direct-current voltage is fed to the anode 2 of reactance tube 1 through radio-frequency choke RFC. This voltage may also be supplied by means of a direct connection to the oscillator tuned circuit L2-C2 if the oscillator tuned circuit is of the type which has the plate voltage on it. Capacitance 3 blocks the reactance tube plate voltage from the tuned circuit L2-C2 of the oscillator tube 20. The oscillator tube 20 is of the electron-coupled type which supplies its output from tuned circuit L3-C3 electronically coupled to the generating circuits and electrodes. Plate voltage is supplied by lead 23 to the anode 25 of tube 20. Voltage for the screen grid 12 of tube 20 is supplied from the plate source by means of potentiometer resistances 21 and 28. The oscillations generated and controlled as to frequency in accordance with control of the grid 24 of tube 1 is supplied through coupling condenser 30 to any utilization means. The circuit if controlled at 24-26 by modulating potentials produces frequency modulated waves. If controlled by AFC potentials oscillations of substantially constant frequency are produced.

In the circuit of Figure 1, the feed-back capacitance C may be eliminated and inductive coupling effected between inductances L1 and L2. This would make the circuit a single-tube equivalent of the circuit of Figure 3 of my United States Patent No. 2,250,095.

The circuit of Figure 2 shows a balanced type of reactance tube circuit which I have found to be very suitable for the production of oscillations of constant frequency due to advantages obtained by the balance. In my United States Patent No. 2,250,095, in Figure 3, I show a circuit employing this principle. In the circuit of said application I employ inductive coupling between the circuit to be tuned and the tuned circuit connected with the reactance tube grids. In the circuit of Figure 2 of the present application capacitive coupling C is employed between the plate 2 and the grid circuits of the reactance tube 1 in the same manner as in Figure 1. However, Figure 2 differs from Figure 1 in that a second tube 52 is provided which gets on its grid 54 a feed-back voltage 180° out of phase with the voltage on the grid 24 of tube 1. That is, in the modification of Figure 2, the grid 24 derives a voltage through C of a particular phase while the grid 54 of tube 52 gets by way of the tuned circuit comprising inductance 56 and condenser 58 a voltage substantially 180° out of phase relative to the said voltage on grid 24. That is, if we assume zero phase of the voltages on anode 2 the voltage impressed by C on grid 24 is shifted 90° while the voltage impressed on the grid 54 is shifted 180° more or 270° relative to the zero phase voltages on the anode 24 of tube 1. Furthermore, if we look at the voltages on the anode 53 as being of zero phase, the voltage on the grid 54 is displaced by 90° so that the phase relation for the reactive effect is established.

It will be noted that voltage is fed back through capacitance C' (which is the natural capacitance between the grid and plate of tube 52) tending

to oppose that fed to circuit 56 by C . The opposition is caused by the fact that the voltage fed back by C is at the opposite end of coil 56 which has the opposite polarity. This opposing feed-back would completely neutralize the reactive effect if C and C' were made equal. However, this equality is intentionally avoided by making C larger than C' so that the predominate feed-back is due to C . This causes the resulting voltage appearing on grid 54 to be 180° out of phase with that fed to grid 24 since that voltage is predominantly fed from C through coil 56.

Since the tuned circuit consisting of 56 and 58 is tuned to the frequency of the energy which is to be modulated, this circuit is resistive and, therefore, acts as though pure resistances were connected from grids 24 and 54 to ground. Hence capacity C in conjunction with this resistive effect forms the phase shifter which produces a 90° displaced voltage on grid 24. Capacity C is adjusted to be of high reactance compared to the resistive effect of 56 so that the current flowing is determined by the capacity and is, therefore, leading the applied voltage from the anode. The drop across the resistive effect of 56 to grid 24 will, therefore, be leading like the current in a condenser and when this voltage is amplified through the tube, the current flowing in the plate circuit of the tube is also leading and the reactive effect is the same as a condenser. The current flowing through the condenser C has thus been amplified by the tube so that the plate circuit of the tube presents a capacitive effect which is variable by the amount that the amplification of the tube is variable.

The voltage appearing on grid 54 of tube 52 is 180° out of phase with that appearing on the grid of tube 1. This makes the voltage on 54 lagging with respect to the anode voltage. The tube then amplifies a current such as would flow through an inductance so that the reactive effect appearing in the plate of tube 52 is inductive and has an effect on tuning which is opposite to that of tube 1. When these two opposing tuning effects produced by the two tubes are properly balanced, the advantage of stability as well as improved range and linearity of reactance variation are obtained. Thus, if variations in the direct-current supply potential to an electrode in the tubes causes variations in the current impulses, the resulting reactive changes are opposed and the total reactive effect is balanced. This causes the tube 1 to produce a compensating capacitive reactance which neutralizes the inductive reactance of the tube 52 as long as the amplifications of the two tubes are balanced. As a consequence, in the absence of modulating potentials and in the presence of variations in power supply potentials on tube electrodes, my tube reactance circuit tends to stabilize the oscillation generator and compensate for said potential variations so that oscillations of substantially constant frequency are generated. Obviously, when the advantages gained by the use of an electron-coupled oscillator are combined with the advantages gained by the use of my self-compensating reactive tube arrangement, oscillations of substantially constant frequency are obtained irrespective of variations in tube electrode voltages.

Differential modulation of tube electrode voltages, such as the screens, suppressor grids, control grids, etc., however, causes an increase in the current impulses to anode 2 at the same time that it causes a decrease in the current impulse to the anode 52 and vice versa. As a result, they

produce an increase of the shunt capacitance at the same time that they produce an increase in the shunt inductance, or vice versa. On the other hand, any cophasal modulation of the element voltages produces an effect in one tube which is compensated for by the other tube so that such undesirable variations are eliminated.

The inductance 56 and condenser 58 are tuned to substantially the mean frequency at which the oscillator 20 is to operate. The reactive effect appears in the common plate circuit of the two tubes which may, as shown, be coupled by condenser 3 to the oscillator tuned circuit L2—C2 for frequency stabilization and/or frequency modulation. The reactance effects obtained by my invention may be applied to the tuned circuit of an amplifier and maintained under complete control of the modulating potentials. As a consequence, this arrangement is well adapted to use for phase modulation.

Variable capacitance C is the feed-back coupling condenser which corresponds to condenser C in Figure 1. This capacitance may be composed of the internal grid-to-plate capacitance of the tube together with added external capacitance, if necessary, or, as I have found, may consist of the unbalance between the grid-to-plate capacitances of the two tubes 2 and 52 and their wiring. Complete control of this capacitance is obtained when C is larger than the condenser C' which may be connected between the grid 54 and plate 52 of the second tube so that the two may be relatively adjusted for complete neutralization or any degree of off-neutralization desired. The capacitance C' usually is composed of the tube capacity only and for that reason is shown by dotted lines.

Figure 2 shows how the balanced circuit may be arranged so as to be controlled by a control potential supplied at 26 with one side at low or ground potential while at the same time retaining the advantage of the balanced reactance tube arrangement and differential modulation. In this arrangement grid control is used and the control potential circuits are connected as shown to the grid 54 of tube 52. The reactive effect will be completely balanced out when the control potential is zero. When positive control potential is applied, the grid 54 of tube 52 is made more positive. This causes tube 52 to draw more cathode current, and, therefore, places both cathodes at a higher positive potential due to the potential drop in cathode resistance 78 shunted by bypass condenser 72. This higher positive cathode potential is equivalent to a higher negative potential on the grid 24 of tube 1. Thus, the required differential control of the gain of the tubes 1 and 52 by the control potentials is obtained. The common cathode resistor 70 causes the grid potential of the one tube to vary in the opposite direction to that of the other. However, this common cathode resistor 70 is not absolutely necessary because the circuit is differentially unbalanced by varying an element voltage of one tube, say 52, without varying that of the other tube, say 1. The common cathode resistor 70 tends to increase the sensitivity to control potentials and increases the range of reactance variation obtainable.

The wave generator indicated by a block diagram at 20' may be as illustrated in Figure 1 or of any type known in the art. The reactive effect provides by the balanced arrangement comprising tubes 1 and 52 stabilizes the operation of the generator which may also be controlled by 78

potentials at 26. A common direct-current source or sources which vary in potential in synchronism supplies the generator and reactance tube arrangement.

5 Figure 3 is a circuit of the balanced type which uses phase shifters which are untuned. The phase shifter for tube 1 consists of resistance R1 and capacitance C2. R1 is made large compared to the reactance of C2 so that the vector relations 10 of the circuit are as shown in Figure 3a. In Figure 3a, E is the applied voltage which is supplied from the common plate circuits of tubes 1 and 52 and I is the current flowing in the phase shifter circuit R1, C2. R1 is the voltage drop across 15 resistor R1 and Xc1 is the voltage drop across capacitance C2. The angle θ between the applied voltage E and the drop across the capacitance C2, which is fed to the grid of tube 1, is seen to be substantially 90° and, more nearly approaches 20 90° as the ratio between R1 and C2 is increased.

The phase shifter for tube 52 consists of capacitance C3 and resistor R2. In this case, the reactance of C3 is made large compared to resistance R2 so that the current is substantially reactive. The vector diagram for the phase shifter R2, C3 is shown in Figure 3b. It can be seen that this type of phase shifter produces a phase shift θ' which is a shift in the opposite direction to that effected by the other type of 25 phase shifter in which the resistance is made large compared to the reactance. This makes the reactive effect of tube 1 opposite to that of tube 52 so that for the balanced condition the reactive effects cancel and differential modulation 30 is required to produce the reactance change. 35

Differential modulation is accomplished in the circuit of Figure 3 by means of the push-pull feed from transformer 90 to the suppressor grids 91 and 92. Capacitances BPC are radio-frequency 40 by-pass condensers and 94 is a blocking condenser. Resistor 96 furnishes a direct-current return for the grid 24 of tube 1.

The reactive effect supplied to generator 20' stabilizes operation of the same which then may 45 be controlled by potentials from 26. Direct-current voltages which vary similarly are used here as in the prior modifications.

In the circuit of Figure 3, capacitances C2 and 50 C3 may be replaced by inductances of the same reactance and the same balance action will be obtained. In all of these balanced circuits there are two methods by which the reactive effect of one tube may be balanced against that of the other so that element voltage supply variations 55 will be neutralized. One of these methods is to balance the amount of voltage fed back to each tube. This might be done by varying the relative sizes of the two halves of the inductance 56 in Figure 2, or by varying the values of R1, C2, and R2, C3, in Figure 3. In any of these cases the 60 balance would be made by increasing the voltage fed back to the tube which did not produce a large enough reactive effect. The second method of balance is by means of the screen-grid balancing potentiometer. In the case of Figure 3, it has been found convenient in practice to have both of these types of balance available and to do so C3 was made variable and a screen-grid balancing 65 potentiometer 68 is included also.

70 70 What is claimed is:

1. In combination with a circuit wherein alternating currents flow and across which a controllable reactive effect is to be provided, a pair of electron discharge devices each having a plurality of electrodes, including a cathode and a

control electrode, means coupling the internal impedance between a pair of electrodes in each of said devices in shunt to at least part of said circuit, reactance means for impressing phase displaced currents from said circuit on two electrodes in each of said devices to produce in said devices reactive effects, a biasing impedance in a common connection between the cathodes of said devices and a point of substantially fixed alternating current potential, a direct current connection between the control electrode of one device and said point potential connected between said point and the control electrode of the other of said devices only, the connections including said impedance being such that variations of the control potential on said one control electrode produces variations in the potential drop in said impedance which changes the bias on the other grid in an opposite sense to differentially control the conductances of the devices to thereby control the reactive effects produced.

2. In combination with a circuit wherein alternating current flows and across which a controllable reactive effect is to be produced, a pair of electron discharge devices each having an anode, a cathode, and a control electrode, a circuit parallel tuned to the frequency of said alternating current connected between the control electrodes of said devices, a connection of low impedance to current of the frequency of said alternating current between a point on said last circuit and the cathodes of said devices, connections coupling the internal impedances between the anode and cathode of each of said devices in shunt to a part at least of said first circuit, a reactance coupling the anode of one of said devices to the control electrode of said one device, an impedance connected between the cathodes of said devices and the control electrode of said one of said devices, and a source of control potentials in series with said impedance between the control electrode of the other of said devices only and the cathodes of said devices, the connections including said impedance being such that variations of the control potential on said one control electrode produces variations in the potential drop in said impedance which changes the bias on the other control electrode in an opposite sense.

3. In a wave length modulation system, a circuit wherein oscillation energy, the wave length of which is to be modulated flows, a pair of electron discharge devices each having an anode, a cathode and a control grid, means coupling the internal impedance between the anode and cathode of each of said devices in shunt to the reactance in said first mentioned circuit, an inductance and a condenser in parallel tuned to the frequency of said oscillatory energy, a condenser coupling the anode of one device to the control grid of said one device, conductors connecting said parallel inductance and condenser between the control grids of said devices, a coupling between a point on said parallel circuit and the cathodes of said devices, an impedance connecting the cathodes of said devices to ground, and a source of modulating potentials connected between the grid of one device only and ground.

4. In a controllable reactance, a pair of electron discharge devices each having an electron receiving electrode, an electron emission electrode and a control electrode, a source of alternating current, means tying the receiving electrodes together and connecting the same to said source to set up on said receiving electrodes alternating voltages of a first phase, connections

between the emission electrodes of said devices and said source to shunt said source by the internal impedances between said receiving electrodes and emission electrodes of the devices, and means for impressing opposed voltages on said control electrodes which are also displaced in phase substantially 90° relative to the voltages on said receiving electrodes including, a parallel circuit parallel tuned to the frequency of said source of alternating current coupled between the control electrodes of said devices, a coupling between said tuned circuit and the emission electrodes, said parallel tuned circuit providing a resistive effect between the control electrode and emission electrode of each device, a reactance coupling the receiving electrode of one device to the control electrode of said one device, and means for relatively varying the conductivity of said devices.

5. In a signalling system, a circuit wherein alternating current flows and across which a controllable reactive effect is to be provided, an electron discharge device having an electron receiving electrode, an electron emission electrode, and an electron flow control electrode, means coupling the impedance between the electron receiving electrode and electron emission electrode of said device in shunt to the reactance in said circuit wherein said alternating current flows, said coupling setting up on said receiving electrode alternating voltage of a first phase, an inductance and a condenser in parallel tuned to the frequency of said alternating current, a reactance coupling the electron receiving electrode of said device to the electron flow control electrode of said device, conductors coupling said parallel inductance and condenser between the electron flow control electrode and electron emission electrode of said device, said coupling reactance and inductance in parallel being arranged to set up on said electron flow control electrode, an alternating voltage which is substantially in phase quadrature with respect to the alternating voltage on said electron receiving electrode and connections for controlling the gain of said device in accordance with control potentials to thereby control the reactive effect produced in said device and added to the reactance in said first mentioned circuit.

6. In a signalling system, a circuit wherein alternating current flows and across which a controllable reactive effect is to be provided, an electron discharge device having an electron receiving electrode, an electron emission electrode, and an electron flow control electrode, means coupling the impedance between the electron receiving electrode and the electron emission electrode of said device in shunt to the reactance in said circuit wherein alternating current flows, said coupling setting up on said receiving electrode alternating voltage of a first phase, an inductance and a condenser in parallel tuned to the frequency of said alternating current, a reactance coupling the electron receiving electrode of said device to the electron flow control electrode of said device, conductors coupling said parallel inductance and condenser between the electron flow control electrode and electron emission electrode of said device, said coupling reactance and inductance in parallel being arranged to set up on said electron flow control electrode, an alternating voltage which is substantially in phase quadrature with respect to the alternating voltage on said electron receiving electrode a resistance in shunt to said parallel inductance and condenser and con-

nections for modulating the gain of said device in accordance with control potentials to thereby control the reactive effect produced in said device and added to said first named circuit.

7. In a wave length modulation system, a circuit wherein oscillatory current the wave length of which is to be modulated flows, a pair of electron discharge devices each having an electron receiving electrode, an electron emission electrode, and an electron flow control electrode, connections coupling the internal impedance between the electron receiving electrode and electron emission electrode of each of said devices in shunt to a part at least of the reactance in said first mentioned circuit, an inductance and a condenser in parallel tuned to the frequency of said oscillatory current, a reactance coupling the electron receiving electrode of one device to the elec-

tron flow control electrode of said one device, conductors coupling said parallel inductance and condenser between the electron flow control electrodes of said devices, a coupling between said parallel inductance and condenser and the electron emission electrodes of said devices, said coupling reactance and parallel tuned circuit serving to set up on the electron flow control electrodes of said devices opposed voltages of the frequency of said oscillatory current which are substantially in phase quadrature relative to the oscillatory voltages on the electron receiving electrodes of said devices, a source of modulating potentials and connections between said source of modulating potentials and one of said devices only for modulating the gain thereof in accordance with signals.
